ADJUSTABLE SUPPORT

Otto E. Trautmann, Irondequoit, N. Y., assignor
to Bausch & Lomb Optical Company, Roches-
ter, N. Y., a corporation of New York

Application August 20, 1935, Serial No. 37,038

5 Claims. (Cl. 254—98)

The present invention relates to supports such as chairs, tables, instrument stands and the like and relates more particularly to electrically driven vertically adjustable supports.

5 One of the objects of the present invention is to provide a motor driven adjustable support which is durable and rugged in construction yet accurate and efficient in operation. Another object is to provide an improved drive means for an 10 adjustable support. A further object is to provide an improved control system for motor driven adjustable supports. Another object is to provide a motor driven support having means for preventing movement beyond predetermined points. 15 These and other objects and advantages reside in certain novel features of construction, arrangement and combinations of parts as will herein-after be more fully set forth and pointed out in the appended claims.

20 Referring to the drawings:

Fig. 1 is a perspective view of a table embodying this invention.

Fig. 2 is a vertical section of same.

Fig. 3 is a fragmentary vertical section taken at 90 degrees to that of Fig. 2 facing away from the switch bracket.

Fig. 4 is a fragmentary vertical section taken at 90 degrees to that of Fig. 2 and facing toward the switch bracket.

30 Fig. 5 is a horizontal section taken on line 5—5 of Fig. 2.

Fig. 6 is a horizontal section through the motor casing and base.

Fig. 7 is a wiring diagram for the control circuits.

Fig. 8 is a modified form of wiring diagram of the control circuits.

A preferred embodiment of my invention is illustrated in the drawings as applied to an instrument table having a base 10 upon which is mounted a casting 11 fixedly carrying a vertical tubular guide 12. A screw 13, rotatably journaled in a bearing 14 in the casting 11, extends upwardly through the tubular guide 12, and a thrust bearing 14' is provided between the lower portion of the screw 13 and the casting 11. A motor 15 is mounted on the base 10 within a housing 16 and serves to rotate the screw 13 through reduction gearing 17 and a flexible coupling 18.

The top 19 of the table is fixed on a support 20 by means of screws 21 and the support 20 is, in turn, fixed to a downwardly extending tubular member 22 by pins or screws 23. The tubular member 22 is telescopically slidable into the tubu-

lar guide and is provided with a longitudinal keyway 24. A key 25, secured to the guide 12 by screws 26, engages in the key way 24 and serves to hold the guide 12 and member 22 against relative rotation. A tubular shield 27 is also fixed 5 to the support 20 and extends downwardly outside of the guide 12 forming a cover to protect the interior mechanism from dust and dirt.

Secured near the bottom of the tubular member 22 by screws 28 is a nut 29 which is threaded on 10 the vertical screw 13. The nut 29 is split at 30 and a screw 31 permits a take-up for wear. Thus it is apparent that upon rotation of the screw 13 by the motor 15 the nut 29 will travel along the screw and thus raise or lower the top 19 of the 15 instrument table.

Referring now to Fig. 7, one circuit for controlling the motor 15 will be described. The two wires 32 and 33 are connected to a source of power and lead respectively to a double throw 20 switch 34 and one side of the armature 35 of the motor 15. The field of the motor 15 is split into two windings 36 and 37 which are opposed. Thus, when the switch 34 is closed to the left, the current flows through the field winding 36 and the 25 motor 15 rotates in one direction while when the switch 35 is closed to the right, the field winding 37 is energized and the motor 15 rotates in opposite direction. In order to prevent movement of the table top 19 beyond predetermined limits, a 30 switch 38 is placed in the circuit with the field winding 36 and a switch 39 is placed in the circuit with the field winding 37. As only one of these switches 38 and 39 is in the circuit at any one time, opening of that switch will stop the rotation of the motor. These switches 38 and 39 are operated automatically in a manner to be hereinafter described.

If the split field wiring shown in Fig. 7 fails to provide sufficient torque to move the table, a 40 four wire system utilizing the entire field can be used as shown in Fig. 8. The two wires 40 and 41 lead from a source of electrical power to one side of the field coils 42 and to the contacts 43 and 44 of a switch 45 respectively. The switch 45 is of the double pole, double throw variety and comprises two tiltable arms 46 and 47 which are fixed together and pivoted to engage selectively the contacts 43 and 48 or the contacts 44 and 49. The armature 50 of the motor 15 is connected 50 across the arms 46 and 47 of the switch 45. The contacts 48 and 49 are each connected to the field coils 42 by the two parallel connectors 51 and 52 respectively. When the switch arms 46 and 47 are closed to the left, current flows through 55

the contacts 43 and 48 and through the connector 51 and when the switch arms 46 and 47 are closed to the right, current flows through the contacts 44 and 49 and through the connector 52. It is 5 obvious from an examination of Fig. 8 that the direction of current flow through the armature 50 is in opposite directions for the two positions of the switch 45 and hence the rotation of the motor 15 is reversed. The tiltable mercury safety 10 switches 38 and 39 are placed in series with the conductors 52 and 51 respectively and serve to stop the motor.

A vertical rod 53, fixed to the casting 11, extends upwardly through the nut 29 and a supporting plate 54 is secured thereon by a member 53' which carries a cover plate 55. A bracket 56 is fixedly mounted on the supporting plate 54 and has an arm 57 extending outwardly at a right angle. The mercury switch 38 is tiltably carried 20 by the arm 57 and is normally held in circuit closing position by a spring 58. This mercury switch 38 is in the circuit controlling the downward movement of the table top 19 and a lug 59 fixed to the tubular member 22, engages the mercury 25 switch 38 and tilts it, thus stopping the motor when the table has reached the position shown in Fig. 2.

The mercury switch 39 is tiltably mounted on the body of the bracket 56 and is normally held 30 in circuit closing position by a spring 60. A plunger 61 is slidably mounted in the plate 54 and is urged away from the mercury switch 39 by a spring 62. The switch 39 is in the circuit controlling the upward movement of the table top 35 19 and when the nut 29 reaches the top of its travel, it engages the plunger 61 and tilts the switch 39 stopping the motor 15.

A switch box 63 is secured to one side of the top 19 of the table and the electric cable 64 extends 40 through a conduit 65 to a plug connector 66 in the base. This plug connector 66 is simply a detachable plug 67 and socket 68 connected respectively to the motor 15 and cable 64. Thus the motor 15 may be removed by removing the plug 67 and it 45 is not necessary otherwise to disturb the wiring. The mechanical details of the connections of the switches 38 and 39 to the cable 64 have been omitted in the interests of clarity but such connections are obvious to one skilled in the art. 50 The switch box 63 has two buttons 69 and 70 controlling respectively the upward and downward movement of the top 19 of the table. As stated above, either of the wiring circuits shown in Figs. 7 and 8 can be used. Pressure on either button 69 or 70 moves the switch 34 or the switch 45 to one extreme position while pressure on the other button moves the switch to the other extreme position. When neither button is depressed the switch is in the neutral position shown 55 in Figs. 7 and 8.

From the foregoing it will be apparent that I am able to obtain the objects of my invention and provide an improved, motor driven, vertically adjustable support. While I have shown and described my invention as applied to an instrument table, it is obvious that the invention could be used with equal facility in instrument stands, chairs or the like. Various modifications can, of course, be made without departing from the spirit of my invention or the scope of the appended claims.

I claim:

1. A device of the character described comprising a base having a vertical tubular guide, a screw 75 rotatably journalled in said base and extending

upward within said guide, a support having a downwardly extending tubular portion in slidably telescoping engagement with said guide, a nut secured to said tubular portion and threaded on said screw, a motor for rotating said screw in either direction, means for energizing said motor, a rod fixed to said base and extending upward through said nut, a bracket carried by said rod above said screw, control means mounted on said bracket for stopping the motor at predetermined 10 limits of travel of said support, and means on said support for actuating said control means.

2. In a device of the character described a base having an upstanding tubular guide, a support having a downwardly extending tubular member slidably telescoping into said guide, means for preventing relative rotation between said tubular member and said guide, a screw rotatably journalled in said base and extending upwardly through said guide, a nut fixed to said tubular member and threaded on said screw, an electric motor carried by said base for rotating said screw, a circuit for energizing said motor to rotate said screw in one direction, a switch in said circuit, a second circuit to energize said motor to rotate said screw in the other direction, a second switch in said second circuit, a rod extending upward from said base through said nut, a bracket carried by said rod above said screw, means for mounting said switches on said bracket, means for urging said switches into circuit closing position, means carried by said support to open the first-named switch to stop the motor when said support has reached a predetermined limit of travel in said one direction, means carried by said support to open the second switch when the motor has reached a predetermined limit of travel in said other direction, and means for selectively connecting said motor in either of said circuits.

3. In a device of the character described a base having an upstanding tubular guide, a support having a downwardly extending tubular member slidably telescoping into said guide, means for preventing relative rotation between said tubular member and said guide, a screw rotatably journalled in said base and extending upwardly through said guide, a nut fixed to said tubular member and threaded on said screw, an electric motor carried by said base for rotating said screw, a circuit for energizing said motor to rotate said screw in one direction, a switch in said circuit, a second circuit to energize said motor to rotate said screw in the other direction, a second switch in said second circuit, a rod extending upward from said base through said nut, a bracket carried by said rod above said screw, means for mounting said switches on said bracket, means for urging said switches into circuit closing position, means carried by said support to open the first-named switch to stop the motor when said support has reached a predetermined limit of travel in said one direction, means carried by said support to open the second switch when the motor has reached a predetermined limit of travel in said other direction, switch means on said support for selectively connecting said motor in either of said circuits, an electric cable connecting said switch means to said motor, and an upstanding hollow conduit secured to said base and extending through said nut, through which the cable passes from said support to said base.

4. In a device of the character described, a base, a vertical screw rotatably journalled in said base, a support vertically slidably mounted upon 75

- said base, a nut on said support cooperating with said screw whereby rotation of said screw actuates said support, an electric motor for driving said screw, a circuit for energizing said motor to 5
5 rotate said screw in one direction, a second circuit for energizing said motor to rotate said screw in the opposite direction, a rod carried by said base and extending upwardly therefrom, a bracket carried by said rod, a mercury switch for each 10
10 circuit tiltably mounted on said bracket, means normally urging both of said switches into circuit closing position, means fixed to said support for tilting one of said switches at the predetermined limit of downward travel of said support, 15
15 means associated with said nut for tilting the other of said switches to stop the motor at the predetermined limit of upward travel of said support and manually operated switch means for selectively connecting said motor in one or the 20
20 other of said circuits.
5. In a device of the character described, a base, a vertical screw rotatably journaled in said base, a support vertically slidably mounted upon said base, a nut on said support cooperating with said screw whereby rotation of said screw actuates said support, an electric motor for driving said screw, a circuit for energizing said motor to 5
5 rotate said screw in one direction, a second circuit for energizing said motor to rotate said screw in the opposite direction, a rod carried by said base and extending upwardly therefrom, a bracket carried by said rod, a mercury switch for each 10
10 circuit tiltably mounted on said bracket, means normally urging both of said switches into circuit closing position, means fixed to said support for tilting one of said switches at the predetermined limit of downward travel of said support, a plunger slidably mounted in said bracket beneath the 15
15 other of said switches, means on said nut for engaging said plunger to tilt said other of said switches to stop the motor at the predetermined limit of upward travel of said support and manually operated switch means carried by said support for selectively connecting said motor in one or the other of said circuits.

OTTO E. TRAUTMANN.
